United States Patent Office.

JULIUS FRANKE, OF QUINCY, ILLINOIS.

Letters Patent No. 74,336, dated February 11, 1868

APPARATUS FOR CUTTING AND PASTING PHOTOGRAPHS.

The Schedule referred to in these Letters Patent and making part of the same.

TO ALL WHOM IT MAY CONCERN:

Be it known that I, JULIUS FRANKE, of Quincy, in the county of Adams, and State of Illinois, have invented a new and useful Photograph-Cutter and Paster; and I do hereby declare the following to be a clear and exact description of the nature thereof, sufficient to enable others skilled in the art to which it appertains to fully understand and use the same, reference being had to the accompanying drawings, making part of this specification, in which—

Figure 1 is a perspective view of the pasting-box.

Figure 2 is an elevation of a key to be hereinafter more fully referred to.

Figure 3 is a top or plan view of the platform.

Figure 4 is a bottom view thereof.

Figure 5 is a side elevation thereof.

Figure 6 is a perspective view of the cutting-device.

Figure 7 is a perspective view of the press.

Figure 8 is a perspective view of a board to be hereinafter referred to.

Similar letters of reference indicate corresponding parts in the several figures.

My invention consists of certain new and useful devices for cutting and pasting photographic pictures, and may be stated to be a pin and cutting-board, a pasting-box and press, whose construction and operation will be hereinafter more fully described.

In the drawings, A, fig. 6, represents a base or foundation adapted to rest on a table or bench, *a*. At one end I secure a number of vertical pins, *b*, placed at equal distances apart, and having their pointed ends free to enter corresponding perforations of a pinning-frame, B, which is constructed of metal, or other suitable material, and of size to correspond to the pictures. C is the back or head-board, having side strips or flanges, *c*. The lower end of this board fits into a suitable opening or groove in the base, A, whereby the board is supported, yet is readily removable. The perforated end of the frame B is cut away so as to slide past the head-board and its flanges. D represents the cutting-board, consisting of a quadrilateral block on which the pictures rest while being cut.

The operation is as follows: A picture is first applied true to the frame B, and having its face upwards. The two are to be held firmly together, and then be pressed down on the base, A. The pins will pass through the picture and the perforations of the frame B, and hold the former in place. The frame should be removed and another picture applied thereto, and undergo the same operation as in the first case, and so on until all pictures have been similarly treated, or as many as are necessary or convenient. The frame resting on the top picture will be held by the pins *b* through its perforations. The back-board is now withdrawn and laid aside for future use. I then mark or pin the top picture at each inside corner of the frame B, after which the said frame is removed. The pictures are now raised sufficiently to allow the insertion of the cutting-block D between the base, A, and the bottom picture, and then are pressed firmly on the block. The pin-marks or dots will form the guide for cutting the pictures. A rule or piece of glass with smooth sides, and of the size of the picture to be cut, will be most suitable, and is to be laid on the picture. A proper knife will cut off the superfluous paper and make the edges of the remaining parts uniform and smooth, and the pictures of the intended size, when they are ready for the pasting-box E, fig. 1.

The pasting-box consists of two sections E' E'' hinged together, and each provided with lids or shutters *d d'*, which are hinged to the sections and held together by hooks and eyes, catches, or any suitable device. On the inner side of each shutter or lid *d d'* there is secured an ear, *e*, holding a curved spring, *F*, which is allowed to slide therein for attachment and detachment. The ends of the spring point inwardly, and thus the springs are arranged in opposite directions when the box is closed. Cross-bars *f f'* extend transversely across the bottom of the section E' of the box, and the top of section E'', and each has grooves, *h h'*, on its sides. Similar grooves are also cut in the side and back end-pieces of the sections E' E''. These cross-bars form receptacles or chambers *f'' f'''*. The cross-bars *f* are provided with pivoted holders, *g*, on their outer face, and the cross-bars *f'* with sliding holders, *g'*. Similar holders *g g'* are placed on the side and end-pieces of the two sections. To the lower section E'' is pivoted a pasting-frame, *G*, constructed by preference of metal, and form-

ing three or more distinct openings to correspond with the receptacle $f' f''$; or with an imaginary or real line bordering the cards. The grooves at the back end or hinged pieces are widened and deepened, and each communicates with an opening, i . Openings, k , are likewise made in the end-pieces of the sections. The outer top edge of the lower section E'' has finger-openings, l . The use of these various parts will be hereinafter more fully explained.

Figs. 3, 4, and 5, represent the platforms designated by H , and intended for the sections $E' E''$, one to support the pictures, the other the cards. Transverse grooves m are cut or made on one face of the platforms, forming pieces, $m' m'' m'''$, which correspond to the size of the picture and the card. Openings, n , are also made at the edges of each piece $m' m'' m'''$, and a portion of the grooves m . In these openings are placed guides which receive sliding catches or holders, $o o'$, having both ends turned into hooks, which limit the play in either direction. Curved springs, I , catch under the outer end of the holders o , and are secured to sliding plates, J . The springs I' of the catches or holders o' are pivoted to the platform H , while the catches o' are secured to slides J' .

It will be perceived that the slides J carry the catches o and their springs I , while the slides J' carry the catches o' alone. Each slide has a hook-end, p , and is operated by means of the key K , fig. 2, which consists of a handle, q , shank, q' , and hook or loop, q'' . The slides are retained in place by suitable guide-pins or equivalent devices. The catches o have lateral or longitudinal motions in the openings n , while the catches o' have transverse motions. The right slides move the holders No. 1 of the pieces $m' m'' m'''$, the left slides conversely the holders No. 2. The springs I' being pivoted, will bear against the hooked ends of the holders or catches o' during all their movements.

The operation is as follows: After the pictures have been withdrawn from the cutting-device, hitherto described, the platforms being properly placed in the sections, the upper section is turned over, having its lid released from the hooks. The platform H in said section, resting on the spring F , will yield and form receptacles into which the pictures are placed, face down and heads pointing towards the hinges, the pivoted catches g being turned to allow of the introduction of the cards. When the desired number has been inserted, the catches are again turned, to slightly project over the cards, and the lid d is then hooked or secured to its section. The lid d' is now released from the section E'' and the pasting-frame thrown open, and the catches g' moved to allow of the introduction of a number of cards corresponding to the pictures, after which the catches are moved so as to project evenly from both sides on the cards. The pasting-frame is returned to its position and the lid d' closed and secured to its section, when I am ready for pasting or gumming.

It will be noticed that during these operations, the springs $I I'$, catches or holders $o o'$, and slides $J J'$, remain unmoved in their places.

Figure 7 represents the press to be employed during the operation. It consists of an upright or standard, r , secured to a table, s , mounted on legs, and carrying grooved pulleys, t , over which pass cords, chains, or belts, u , one end of each of which is secured to the treadle t resting on the floor, and the other ends to a flat-weighted block, u' , from the under side of which are secured cords or wires, u'' , which pass through openings in the table, and are connected to a weight, u''' . Placing the open box to the right of the press, I apply paste to the cards, the space being limited by the pasting-frame G . This frame is then to be raised and thrown off from its section, and the box closed, the top being the right-hand section. I now open the box and give the cards a light hand-pressure; it being seen that the lower picture has meanwhile adhered to the top card, which should be withdrawn from the box and placed under the weight u''' , which is raised by means of the treadle t' , and then lowers itself, when it will rest on the complete picture.

The pasting and pressing-processes are alternately repeated, and so continued until the whole number of pictures are completed and the press is full, when the pictures should be taken out and placed under a heavier weight or small press.

Should it be desired to use my device for small pictures, I withdraw the spring of the lower shutter d' , and, in place thereof, use the device shown in fig. 8, which consists of a quadrilateral plate or board, v , which is transversely grooved, and provided with ways in which move or slide strips, w , the upper side of each of which is bevelled about two-thirds of its length to the end thereof. The strips w are to be removed and the back-board v introduced between the lid d' and the springs of the platform. The box being open, the lower section will rest on its lid with the interposed board v . The pasting-frame G is now thrown back and off from the box, when it will be noticed that the catches $o o'$ are raised upwards beyond the surface of the pieces $m' m'' m'''$.

A number of cards are now introduced between each set of holders $o o'$. The key being applied to the hooked ends p of the slides $J J'$, these slides are drawn in the directions of the openings k i. The grooves $h h'$, of the cross-bars ff' , and the grooves $h'' h'''$, of the back and side pieces of the section $E' E''$, allow the catches to rise and fall therein, as well as their introduction with the platforms. Each of the grooves h'' of the upper section, and the grooves h''' of the lower section, is widened and deepened at its centre, as shown at x , so as to receive the ends of the slides $J J'$. The key being again applied and the slides forced inwards, the small cards will be held by the catches or holders $o o'$.

The same operation is repeated for the pictures in the upper section, excepting that a metal plate of any suitable kind and of a size to correspond to the pictures, should be applied between the holders, so as to prevent too much strain on the paper. Now, I return the sliding strips w to the back-board v , and apply the latter between the lid and springs, with the strips against the lid, and the rounded or bevelled edge at the hinged end. By closing the lid, the catches or card-holders are further moved, and the full number of cards or pictures are introduced between them. The board is then withdrawn, the holders g or g' turned, and the back spring F returned to place, and the lids secured to their sections, when I am ready to paste the pictures and cards as in the first operation.

In pasting small pictures, it is necessary that the frame G should be substituted for one of corresponding size, or a movable frame be employed, so constructed as to be extended or contracted as occasion may require. I am enabled to cut and paste pictures and cards of any size or shape, it only being necessary to have the apparatus of proper dimensions and proportions.

Having thus described my invention, what I claim as new, and desire to secure by Letters Patent, is—

1. The box E, back springs F, movable platform H, and pasting-frame, combined and operating substantially as and for the purpose described.
2. The reciprocating card-holders or catches o o', slides J J', and springs I I', in combination with the platform H, operating with the board v and its strips w, and the box E and springs F, substantially as and for the purpose described.
3. The board v and removable strip w, for the purpose described, substantially as specified.
4. The arrangement of the slides in three or more divisions so as to hold three or more sets of cards and pictures, substantially in the manner represented and described.
5. The pulleys t, belt u, treadle t', block u', and weight u'', combined and operating as described, and adapted for the purpose specified.
6. The pin and cutting-board constructed of the removable guide-board C, frame B, removable block D, and pins b, substantially as described for the purpose specified.

JULIUS FRANKE.
